BRAKING APPARATUS

Matthew H. Loughridge, Bogota, N. J.

Application October 5, 1928, Serial No. 310,618

38 Claims. (Cl. 303—18)

This invention relates to a brake controlling system and apparatus particularly adapted for railway trains and to an automatic train control system for controlling traffic on a railroad.

5 The objects of the invention are to provide a braking system which is manually controlled and which is automatically controlled and in which the brakes may be applied or released manually or automatically, progressively to the extent desired; a system in which the manual control suspends the operation of the automatic control only to the extent to which the manual control is effective and in which the automatic control becomes operative as the manual control is released; 10 a system in which the automatic control requires the operation of a forestalling device each time it becomes operative to prevent a brake application, and when the forestalling device is operated, the brake control is subject to control by the speed of the vehicle. Another object is to secure an intermittent venting of the train brake pipe. 15 Another object of the invention is to provide a speed control system using the principle of the Venturi tube, designed for movements in both directions and for a variety of speed controls.

Other objects of the invention will appear from the following specification and the accompanying drawings, in which:

Fig. 1 is a sectional elevation of the brake controlling apparatus,

Fig. 2 is a transverse section on line 2—2 of Fig. 1,

Fig. 3 is a transverse section on line 3—3 of Fig. 1,

Fig. 4 is a transverse section of line 4—4 of Fig. 1,

Fig. 5 is a view, partly in section and partly in diagram, showing the connections and operation of the automatic control,

Fig. 6 is a plan view of the motion plate and plunger of the manual control,

Fig. 7 is a sectional view of the control magnet and stepping valve,

Fig. 8 is a view of the stepping valve in section,

Fig. 9 is a fragmentary elevation of the speed control device,

Fig. 10 is a longitudinal section of a double ended Venturi tube adapted for speed control purposes,

Fig. 11 is a front elevation, partly in section, of the Venturi system,

Fig. 12 is a detail showing the method of obtaining direction control in the Venturi tube and

Fig. 13 is a circuit arrangement for the control magnets.

Fig. 14 is an enlarged sectional elevation of the equalizing valve shown in Fig. 1 in the released position;

Fig. 15 is a sectional elevation corresponding to Fig. 14 with the equalizing valve in the application position;

Fig. 16 is an enlarged sectional view of the stepping valve shown in Fig. 8 in the released position, and

Fig. 17 is a sectional view corresponding to Fig. 16 with the mechanism in the application position.

The application mechanism

This invention comprises a brake application valve biased by a spring to the most retarding position and held released by a walking beam one end of which is manually controlled and the other end of which is controlled automatically. When the manual control is in operation conditions are set up to prevent the operation of the automatic control, but the automatic control remains effective for a greater degree of braking than is applied by the manual system.

In the drawings, 11 is the valve cylinder in which the valve 12 slides, 13 is a cavity in the valve, 14 is an air supply duct, 15 connects to chamber 22, 16 connects to chamber 20, 17 connects to chamber 21 and 18 connects to chamber 19 from the valve cylinder 11 as will be understood from Fig. 2. This cylinder is normally vented to atmosphere through the passage 30 and when the valve is in the raised or clear position shown, the expansion chambers 19, 20 and 21 are at atmospheric pressure and chamber 22 is connected with the air supply duct 14 through cavity 13.

The chamber 22 connects to the cylindrical expansion chamber 23 through port 25 (Fig. 14) and has the piston 26 working therein. The stem of piston 26 closes the exhaust port 28 connecting chamber 27 with the exhaust pipe 29 when the piston is in the lower position. When the piston is raised to its fullest extent it closes the aperture 24 connecting chamber 22 with the cavity 13 in the valve. When port 28 is open the train line 32 is exhausted through passage 31 and the brakes are applied in a well known manner proportional to the extent of the exhausting. If the exhausting is restricted, or varied, the brake application will be correspondingly varied. As this is a desirable feature in braking trains, the ports controlled by piston 26 are varied as the brakes are applied. For instance, raising 26 partially closes 24 and temporarily restricts the exhaust

from chambers 22 and 23 until the brake pipe pressure in 21 is reduced below the pressure in 22—23. This lowers the piston 26, thereby closing, or partially closing, the vent port 28 until the pressure in 22—23 is further reduced through port 24, when piston 26 is again raised to open port 28 and to partially close port 24. This movement by piston 26 is repeated until chambers 22—23 and the reservoir with which they are connected are equalized in pressure. From this operation, it will be noted that the train line is not exhausted by a continuous flow of air through the vent 28, but instead, the flow is intermittently tapered so that the brakes are applied with increasing pressures which are separated by an interval of time.

The brake pipe 32 connects through passage 31 with the chamber 21. It also connects to the cylinder 33 having the piston 34 normally held in its lower position by the spring 35. The upper portion of piston 34 is subject to the air pressure in chamber 23 through the port 37. The piston 34 has secured thereto the hollow plunger 36 which connects with the main reservoir supply pipe MR and when in the lowered position permits the train line 32 to be charged from MR through the port in the side of 36, but when piston 34 is raised due to a lowering of the pressure above the piston, the hollow plunger 36 is raised and the MR pipe is cut off.

The valve 12 is controlled by the plunger 42 and is normally biased to the controlling position by the spring 41. The plunger 42 is controlled by the walking beam 43 which is supported at one end by 44 and at the opposite end by 61.

The manual control

The supporting stem 44 is bifurcated at 45 to receive the arcuate motion plate 46 which is provided with oblique slots in steps connecting the parallel slots 51, 52, 53, and 54, Fig. 6. A pin 47 engaging these slots and the stem 44 moves the stem vertically up and down, in response to movements of the motion plate. The stem 44 terminates in a piston 48 working in the dash pot 49 which is controlled by the valve 50 with the object of cushioning the downward movement of this stem as forced by spring 41. The arcuate motion plate is connected at 70—70 to the rotary valve 68 manually operated by handle 69, Fig. 5, as hereinafter described.

The automatic control

The end of the walking beam 43 is supported by a second walking beam 61 supported by the plungers 62 and 63. Plunger 62 connects with piston 64 in cylinder 65 and plunger 63 connects with piston 66 in cylinder 67. When these cylinders are under air pressure the plungers are raised, both ends of walking beam 61 are raised and 43 is raised to its extreme position. When air is exhausted from either of these cylinders the walking beam 61 is lowered at one end, correspondingly lowering 43 and when both of these cylinders are exhausted both ends of 61 are lowered and 43 is lowered to a greater extent.

The rotary valve 68 is cored at 71 to fit the projecting end 72 of the valve cylinder and rotates thereon, being held in place by the collar 73. Air passages are enclosed between the lower face of 68 and the top of the application mechanism, which passages are shown diagrammatically in Fig. 5 with the air connections. Cylinder 65 by pipe 74 connects to the slot 75 in 68 and pipe 80 leading therefrom connects to the forestalling

device 81 and associated apparatus. Cylinder 67 connects by pipe 76 to the slot 77 and by pipe 78 connects to the forestalling device 79. It should be understood that pipes 74, 76, 78 and 80 lead from stationary apertures or passages in the casting of the application mechanism, over which apertures the arcuate slots 75 and 77 move with the rotary valve 68. Air pressure through pipe 84 connects to the arcuate slots 82 and 83 in the casting below the valve 68. The slot 82 aligns circumferentially with the slot 75 and the slot 83 aligns with the slot 77.

The forestalling system

The forestalling system is manually operated to synchronize with the trackway control as disclosed in U. S. Patent 1,627,567, May 10, 1927. Briefly, this comprises a valve operated by the handle 88 to either of two positions. In the position shown, pipe 80 connects to the interior 85 of the valve member and through port 86 connects to pipe 87 while pipe 90 is closed. When handle 88 is moved to its other position port 86 is closed and pipe 90 connects with chamber 85 through port 89. The movement of handle 88 thus alternately changes the connections between pipes 87 and 90 and pipe 80.

The trackway controls and stepping valve

The magnet 91, Fig. 7, is controlled from the trackway by any suitable means such as disclosed in U. S. Patent 1,859,591, May 24, 1932. This magnet controls the valve 93 through the armature 92 and is energized under clear conditions. In the deenergized position shown it will be noted that the air supply pipe 94 is closed and that cylinder 98 and timing reservoir 97 are exhausted to atmosphere through passage 96, port 95 and alarm whistle 95a. This permits the spring 100 to pull the rocking arm 101 and ratchet detent 102 backwards, thereby rotating the ratchet wheel 103 and the stem 104 to the extent of one tooth or step.

When magnet 91 is energized the position of valve 93 is reversed, the port 95 is closed and air under pressure from 94 is supplied to timing reservoir 97 and cylinder 98 through passage 96. This moves the piston 99 forward and brings the detent 102 into engagement with the next ratchet tooth, and thus into position to rotate stem 104 and valve 108 another step when 91 is again deenergized.

The ratchet wheel 103 operates a rotary valve 108 Figs. 16—17, which has a double row of ports, one row 106—106a aligning with pipe 87 and the other row 109—109a aligning with pipe 90 as indicated by the dotted lines. The ports 106a—109 connect with chamber 110 and the ports 109a and 106 as indicated by the dotted lines connect with the exhaust 105 through the valve body 108. A new pair of ports align with these pipes at each step of the valve, as shown in Fig. 8, which, in the position shown, connects pipe 87 through port 107 to the chamber 110 while pipe 90 connects to exhaust 105, but upon the rotation of valve 108 by one step of the ratchet wheel, pipe 87 is connected to exhaust through 106 and pipe 90 connects to chamber 110 through port 109 and these pipes are alternately connected and disconnected with chamber 110 and exhaust for each step of wheel 103. Chamber 110 through port 110a connects with chamber 115a housing spring 115 and with valve cavity 111, which in the position shown in Fig. 16 connects through port 112a with the air supply 75

pipe 112. This is the position when magnet 91 is energized, or the release position, but when this magnet is deenergized, the valve 112b is moved to the position indicated in Fig. 17 in which the air supply pipe 112 is cut off and the cavity 111 connects through port 112a with pipe 116. This is caused by the valve 93 permitting the air to exhaust from cylinder 98 through passage 96. A port 113 at the end of cylinder 114 connects this cylinder with cylinder 98 and permits the air pressure to equalize in these cylinders. The spring 115 is adjusted to move the piston 114a and the valve 112b connected therewith to the position shown in Fig. 17 before piston 99 moves to blank the port 113. That is, the air pressure is sufficiently reduced in cylinder 114 to permit the movement of valve 112b before port 113 is closed.

When magnet 91 is energized the valve 93 connects the air supply pipe 94 with cylinder 98 and moves the piston 99 to the position shown in Fig. 16, this uncovers the port 113 and admits air pressure to the face of piston 114a, moving this piston to the position shown in Fig. 16. The movement of piston 99 moves the detent 102 to engage another tooth of stepping wheel 103 for the next operation of valve 108. Pipe 116 connects to the speed control device Fig. 9 and under certain conditions maintains the air supply that was cut off from pipe 112 and under other conditions (high speed) pipe 116 is connected to atmosphere thereby leading to a brake application.

The speed control system

Speed control is obtained by restricting the air supply to pipe 116 under predetermined conditions of speed. Under low speed and with magnet 91 deenergized, this pipe is supplied with air under pressure which maintains valve, Fig. 1, in the released position, but under high speed this pressure is exhausted, thereby producing a braking effect. This will be understood by considering the air pressure to cylinder 65 operating the brake valve. This pressure is maintained through pipe 14, slot 75, pipe 80, valve 81, pipe 81, valve 108, chambers 110, 115a, and cavity 111 to port 112a connecting to pipe 116 in the application position. The speed control device, Fig. 11 connects pipe 116 to an air supply pipe 117 at a predetermined low speed, or connects this pipe to atmosphere through 137 at high speed. Speed control may be secured in various ways, as for instance by the centrifuge disclosed in U. S. Patent 1,807,596, June 2, 1931. In the present disclosure speed control is obtained for movements in both directions by a double ended Venturi tube mounted on the vehicle and arranged to vary the air pressure in a cylinder having a valve mechanism, proportionally to the speed of the vehicle.

In Fig. 10, the side of the vehicle is indicated by 121 in which flared apertures A and B are provided leading to the tapered Venturi tube 127 with the restricted orifice in the centre at 123. The crescent shaped projections 122 may be provided to direct the air into the tubes A and B by increasing the air pressure at the entrance of the leading tube and creating a partial vacuum at the orifice of the following tube. The outer apertures may be supported in the centre by the collar 124 as shown. Mounted on the axial centre at the narrowest part of the tube are the smaller double ended tubes 125-126. These are supported by the valve head 129 formed integral

with casting 124 and having a passage 131 connecting with the cylinder 132 in the base 118. The piston 133 in this cylinder is normally maintained in its lower position by spring 134 and is connected with the valve mechanism 139. In 5 the position shown, air pressure is supplied by pipe 117 through cavity 138 to pipes 119 and 116.

When the air pressure is reduced in cylinder 132, the pressure in cylinder 136 moves piston 135 upwards shutting off air supply from pipe 10 117 through cavity 138 in valve 139 to pipe 116 and connecting this pipe to cylinder 136 where it connects to atmosphere by port 137. As the sub-atmospheric pressure is further reduced in cylinder 132, pipe 119 is cut off from cavity 138 15 and exhausted into cylinder 136. As atmospheric pressure in cylinder 132 is restored the valve 139 is restored and air pressure is reestablished in pipes 119 and 116 from pipe 117. It should be noted that the air in cylinder 65 is maintained by 20 pipe 116 in the speed control position so that if this pipe exhausts, cylinder 65 exhausts and thereby produces a control effect. Pipe 119 may, similarly, exhaust cylinder 67 under speed control conditions. The air exhausted into cylinder 25 136 from pipes 116 and 119 has a tendency to raise piston 133 but this condition is substantially neutralized by the large orifice 137 connecting to atmosphere.

The air pressure in cylinder 132 is reduced by 30 the Venturi tubes 125-126 as the device moves at speed along the track. It will be noted that the Venturi tube is symmetrical about its transverse axis and is adapted to pass air currents therethrough in either direction according to 35 the direction of running and in order to obtain the Venturi effect in each direction a change over mechanism is provided which automatically connects cylinder 132 with the trailing Venturi tube. The Venturi effect referred to is well understood 40 in aerodynamics. The flow through the tube is accelerated from the increase in velocity and consequent loss of pressure caused by a reduction in the cross-sectional area of the tube. Its operation is pneumatic and it is not to be confused with the mechanical displacement of a 45 vane by air currents.

The direction control of the venturi will be understood from Fig. 12. The blades 141 are suspended in the tube, one being pivoted at 142 at 50 one end of the venturi and the other being pivoted at 144 at the opposite end. It is apparent that these blades will be deflected in the direction of the air current through the tube. A rotary valve 149 is rotated by arm 148 connected by rods 145 55 and 146 with the blades 141-141. This valve is provided with a cavity 129 which, when arm 148 moves to the right connects the port 128 with the passage 131, and when arm 148 moves to the left port 130 is connected with passage 131. 60 When the apparatus is in the neutral position as shown, a passage 151 shown in dotted outline connects passage 131 with atmosphere.

If the vehicle carrying the venturi is moving to the left, the air current therethrough will be 65 relatively towards the right. This moves the blades 141 and thereby connects tube 126 with the cylinder 132. On the other hand, if the direction of movement of the vehicle is reversed, the blades 141 will be reversed and cylinder 132 will 70 be connected with tube 125. Air is exhausted from cylinder 132 by the well known Venturi principle, proportionally to the speed of the vehicle and consequently valve 139 is moved proportionally to the speed of the vehicle. When the ve- 75

hicle stops the air pressure in 132 is equalized through 151, or may be equalized through the passage 131 as the Venturi effect decreases.

This venturi is provided with side ports so that it is not materially influenced by adverse wind currents and the opposite cylinder 136 also receives air through the side port 137 so that variations in the density of the air, due to tunnels, etc., are neutralized.

10

The apparatus

In the apparatus described it will be noted that the control mechanism is embodied in one casting and that long pipe connections are avoided, 15 the only pipes used being those to the stepping valve and to the speed control apparatus. The control apparatus is embodied in a casting which replaces the engineer's brake valve, which casting is bored from either end for the operating 20 cylinders and valves. The controlling valve is in the centre and the expansion chambers are built around it with the passages between the various parts formed in the casting. The air for operating the pistons comes from the opposite 25 end of the line so that a false operation cannot be obtained by the accidental closing of the pipes.

The forestalling or synchronizing valves are embodied in the control apparatus as shown in Fig. 3 so that the apparatus is manipulated by 30 handle 69 and by the handle 88 of the forestalling valves. It should be noted that the walking beam arrangement for supporting stem 42 includes any equivalent floating connection such as a rack and pinion that may be substituted for this construction.

The speed control arrangement avoids the use of apparatus driven by the running gear of the vehicle, is automatically operative for both directions and the tubes 125—126 are mounted in 40 a casting which forms the cover of cylinder 132 so that the apparatus is compact and not likely to get out of order.

It will be noted that each operation of the stepping valve 105 lowers the walking beam 43 to apply the brakes, but if a second operation were obtained without the corresponding operation of the forestalling valve, it would cancel the first operation. This is avoided by wiring the control valve as indicated in Fig. 13. The disc 50 103a rotates with shaft 104 and carries the contacts 156, 158, etc., in line with contact finger 160 and the contacts 155, 157, etc., in line with the contact finger 159, there being a contact for each tooth in wheel 103. Contact finger 154 makes 55 contact with the inner and outer row of contacts and by wire 153 connects to control magnet 91. The handle 86 of the forestalling valve carries the contact plate 164 which is connected to wire 166 and in one position makes contact with finger 163 connected to wire 161 and in the opposite position makes contact with finger 165 connected to wire 162.

In the position shown the circuit of 91 through wires 153 and 162 is interrupted at contact finger 65 165 until handle 88 is reversed. That is, 88 must be moved to synchronize with the movement of the stepping wheel 103 before 91 can be again energized. After 88 has been moved it will be observed that the next step of wheel 103 brings 70 contact 154 and 155 into circuit with wire 161 and 91 cannot be energized until 88 is moved to establish the circuit between 153 and 164. The remaining part of the controlling circuit for 91 is not shown in this diagram.

75 It should be understood that the forestalling

device 79 is constructed similarly to 81 and that the air pipes leading therefrom connect with a second stepping valve similar to that shown in Fig. 7, and controlled by another magnet similar to 91 which is responsive to track conditions. The pipe 116 leading from the second stepping valve may connect to pipe 119 of the speed control device, Fig. 9, and thus be operative under different speed conditions from pipe 116 controlled by valve 81. This part, for simplicity, is omitted from the drawings, being a duplication of the apparatus already illustrated.

OPERATION—CASE I

Manual control of the brakes

15

When the automatic control is released by air pressure in cylinders 65 and 67, the brakes are manually operated by handle 69. When in position *a* the pin 47 occupies slot 51 and 44 may be raised to the extreme position. This raises valve 12 to its extreme position and main air supply is connected through 14, 13 and 15 with cylinder 22 which closes exhaust 28 and permits 34 to seat and connect MR with the train line, thus releasing the brakes. This is the running position.

When handle 69 is moved to position *b*, pin 47 occupies slot 52 and walking beam 43 is lowered with valve 12. This closes the air supply 14 and connects 15 with 16, reducing the air pressure in 22 and 23 by the volume of the expansion reservoir 20. This permits piston 26 to unseat valve 28 until the pressure in chamber 21 is equalized with the pressure above the piston, after which the valve 28 is reseated. This causes a partial reduction of the train line pressure and a corresponding braking effect which is maintained by the reduced pressure above piston 26. This may be called a service application.

When the apparatus operates to apply the brakes, it is, in most cases, necessary to close the connection from the main reservoir to the brake pipe, to prevent the brakes being released, or to insure quicker operation of the brake application. In the prior art this is usually provided for through a mechanical connection with the application valve.

In this invention the brake feed pipe from the main reservoir is controlled pneumatically by the piston 34 and the slide valve 36 secured thereto as best shown in Figs. 14 and 15. This piston responds to the pressure in chambers 22, 23, and 35a which are equalized through the ports 25 and 37. The initial lowering of the pressure in these chambers lowers the pressure above piston 34 to such an extent that the train line pressure in chamber 33 raises the piston against spring 35 to the position shown in Fig. 15 in which the port 36a to the main reservoir is closed. When running conditions are restored, the air pressure in chambers 22, 23, and 35a is restored from the supply 14 and piston 34 is lowered to the position shown in Fig. 14 connecting the main reservoir by port 36a to chamber 33, to release the brakes.

It is usual to provide a reducing valve between the main reservoir supply and the brake pipe so that in practice main reservoir supply may represent, approximately, one hundred pounds' pressure and the brake pipe may represent seventy pounds' pressure. This reducing valve is not shown in the drawings. If 14 is connected with the main air supply the chambers 22 and 23 and the chamber 35a in which spring 35 is located

75

will normally stand at this pressure, while the pressure in the brake pipe 32 and the chambers 27 and 33 will stand approximately at seventy pounds pressure. This will cause the valve 28 to seat and the valve 36 to seat and establish connection from MR to pipe 32 through port 36a. When the pressure in chambers 22, 23 and the chamber 35a above the piston 34 is expanded into the expansion reservoir 20, the valve 28 is unseated and the valve 36 is unseated. This condition continues while the brake pipe pressure is being exhausted through the vent 29, and until a reduction has been made sufficient to cause the remaining pressure in chamber 22 to close the port 28.

At this time the valve 36 may be again seated, depending upon the friction of the piston 34 in its cylinder and as it becomes seated, under these conditions, a connection will be established. However, as soon as pressure from MR begins to rise in chamber 33, piston 34 is raised, valve 36a is closed and the recharging is cut off.

When handle 69 is moved to position c, the pin 47 occupies slot 53 which lowers walking beam 43 and valve 12 to the next stage. This connects chamber 22 to expansion reservoirs 20 and 21 through ducts 16 and 17 and causes a further reduction of pressure on piston 26 which unseats valve 28 and releases the pressure in chamber 27 until the pressure above the piston is equalized by a further reduction of train line pressure and an increased application of the brakes caused thereby. This may be called an emergency application.

When handle 69 is moved to position d, the pin 47 occupies slot 54 and the valve 12 is thereby lowered to its maximum extent. This connects chamber 22 with the expansion reservoirs 19, 20 and 21 through ducts 16, 17 and 18 and reduces the pressure on piston 26 to a low value. This unseats valve 28 to make the maximum train line reduction and maximum brake application.

The handle 69 can be moved from position a to position d as rapidly as the plunger 48 can be moved in the dash pot 49. The dash pot is regulated to prevent a sudden movement of the valve 12 under the action of spring 41. It is apparent that the handle 69 can be moved from the position d towards position a to any extent so that the braking effect may thereby be regulated. When the handle is fully restored to position a air pressure from port 14 is connected through 15 to cylinder 22, reservoir 23 and cylinder 35a thus restoring running conditions by seating valve 28, closing the exhaust and connecting MR to train pipe 32. This manual operation is always obtainable under all conditions.

OPERATION—CASE II

Automatic control of brakes

The automatic control is obtained through the magnet 91. When this magnet is energized and the valve 88 synchronized with the stepping valve, air is supplied from pipe 112, through valve 108, and either of pipes 87, 90, through valve 81 to pipe 80 and valve 68 to cylinder 65 raising one end of walking beam 61. A corresponding magnet operates with valve 79 supplying air pressure to pipe 78 and through valve 68 to cylinder 67 raising the other end of walking beam 61. Thus, as long as the air pressure is maintained the valve 12 is maintained in the raised position as far as the automatic control is concerned.

When the magnet 91 is deenergized valve 108 makes one step which vents the pipe under pressure connecting to valve 81 and this will vent the cylinder 65 unless the synchronizing valve 88 is reversed. That is, the movement of the piston 99 must be forestalled to prevent the walking beam 43 being lowered, and the consequent immediate application of the brakes. After magnet 91 is deenergized a time interval must elapse before piston 99 is moved viz, until the pressure in the timing cylinder 97 is exhausted through the alarm whistle 95a. The sounding of the whistle is a warning to operate the forestalling device and prevent an immediate brake application which will occur when cylinder 65 and the timing reservoir 80a are exhausted.

After the forestalling device has been operated and during the time 91 is deenergized, the air pressure to cylinder 65 is controlled by the speed of the vehicle through pipe 116. When the speed is low this pipe is supplied with air pressure from 117, but when the speed is above a predetermined value this pipe is vented and through it the air in 65 is vented and the walking beam 43 is lowered. As soon as 91 is energized and piston 99 moved to the active position, piston 118a is moved to connect the air supply 112 to the cylinder 65, thereby raising the walking beam and releasing the brakes.

The cylinders 65 and 67 are controlled by similar mechanisms but they may operate under different speed conditions and the controlling magnets may be controlled over different portions of track. It will be noted that each cylinder lowers the walking beam to the same extent and the lowering effects produced by one cylinder is added to the effects produced by the other cylinder. In practice it may be desirable to have the movements of the walking beam caused by 65 and 67 correspond with the movements of 44 in slots 52 and 53.

The lowering and raising of the walking beam by the cylinders 65 and 67 produce movements of valve 12 similar to that already described with corresponding braking effects. In the automatic operation it should be noted that the brakes are always applied after a time interval, when the controlling magnet is deenergized, if the forestalling device is not operated, but if this device is operated at the proper time, the brake application becomes subject to speed control.

OPERATION—CASE III

Combined manual and automatic control

It is apparent that the floating connection 43 mechanically connects the manual and the automatic controlling mechanisms and controls the brakes through the single valve 12. It is generally recognized in practice that if the brakes are properly controlled manually, the automatic control is unnecessary, but, on the other hand, if the manual control is released, or if it is applied to a lesser extent than that required by the automatic control, then the automatic control should become effective to apply the brakes to the extent which the manual control has failed to apply them. This result is secured in the present invention by making the operation of the manual control progressively suspend the operation of the automatic control as the manual control progressively applies the brakes and reversing this conditions as the manual control is released.

When the brake controller 69 is moved to po-

sition *b* to produce the first stage of braking, pipe 80 is cut off and slot 75 connects with the slot 82 thus supplying air pressure directly from pipe 84 to cylinder 65. Thus when the first stage of braking is produced manually, the first stage of automatic braking is suspended. If an automatic control is now received it will not become effective until the manual braking is released.

- 10 When the controller 69 is moved to the position *c*, air is supplied to cylinder 65 through slot 75 as described and air is supplied to cylinder 67 through slot 77 and slot 83 while pipe 78 is cut off. Thus both cylinders 65 and 67 are under pressure suspending the automatic operation while the manual control is operative. If pipes 78 and 80 are both vented by the automatic control while the manual control is in position *c* the manual control suspends the automatic control, 15 but if the manual control is afterwards partially released by moving handle 69 to position *b* then the slots 77 and 83 are disconnected and the connection between pipe 78 and slot 77 is restored and the cylinder 67 is vented through pipe 78. 20 This lowers walking beam 43 to the extent of another stage of braking and the braking effect is the same as if the controller were in position *c*. The manual control thus suspends the automatic control when the automatic braking effects do not exceed those applied manually, but the automatic control is always effective for braking control in excess of the manual control.

The brake controlling apparatus can be constructed in a variety of forms of which a typical arrangement has been selected to illustrate the working principles of the invention, other forms of the invention may be applied by those skilled in the art without departing from the intent and scope hereof.

- 35 40 This invention comprises a train control system and braking apparatus used in connection with the ordinary air brake systems. The system includes E. P. valve 91 which is responsive to traffic conditions on the trackway by any suitable controlling system and this valve in turn operates a stepping valve 103 making one step for each control effect obtained from the trackway. The stepping valve has connected therewith, a pair of pipes, 87-90 one of which is active 45 to connect air pressure through a manually controlled forestalling valve 81 to the brake controlling apparatus operated by cylinder 66 while the other pipe remains inactive. When a control effect has been obtained the stepping valve is moved to change the control, from the active to the inactive pipe and, under these conditions, the forestalling valve must be changed in position, either before the stepping valve is operated or immediately thereafter so as to maintain the 50 air pressure in cylinder 66 and prevent a brake application.

The air supply to the stepping valve for operating the brake application valve is obtained direct, under normal conditions, but is obtained through a speed control device 118 which connects by pipe 116 with the stepping valve. The speed control device operates to exhaust pipe 116 at high speed and to connect air pressure to the pipe at restricted speeds so that when a control effect is obtained it can be manually forestalled provided the speed does not exceed a predetermined value.

70 75 A pair of E. P. valves, similar to 91 with the associated stepping valve, manual release and speed control are contemplated in the system, one

of which operates at a lower speed than the other. These devices operate through the cylinder 64 and cylinder 66 and the walking beam 61 to move the slide valve 12 in the central part of the valve housing against spring 41. The beam 43 is also operated manually by a notched plate which is designed to lower the slide valve 12 in stages, each stage corresponding to a different degree of braking. When the manual control is operated to the same extent as the automatic control through cylinder 64 and cylinder 66, the automatic control is thereby suspended by supplying air to the cylinders 64 and 66 through the manipulation of the manually operated valve. However, if the manually operated valve is moved 15 to the release position, when the automatic control is established, the automatic control immediately becomes effective.

The brake pipe is vented by an equalizing valve which has pressure on one side vented into a 20 series of expansion reservoirs corresponding with the position of valve 12. In order, however, to provide an intermittent venting of the train line in preference to a continuous venting during the brake application process, the equalizing valve 25 has a double action in which it restricts the venting of the pressure above the valve and temporarily reestablishes equalization, causing this valve to assume the normal position and close the venting of the train line until further reduction has been made into the equalizing reservoir when it is again unseated to vent the train line and in this way an intermittent venting of the train line may be secured.

The brake valve with the equalizing valve is 35 made in one casting in which the valves are centrally located and the expansion reservoirs are placed circumferentially around these valves so as to economize on space and eliminate outside pipe connections.

40 Speed control is obtained by a specifically designed Venturi tube which is made double ended and with slide ports for the air entrance. A valve is operated by the venturi action in reducing the atmospheric pressure bearing on this 45 valve which moves to an extent corresponding with the speed of the vehicle. This valve, in turn, cooperates with the stepping valve in the operation of the brake valve mechanism.

Having thus described my invention, I claim: 50

1. A brake controlling mechanism for an air brake system comprising a brake valve for producing brake applications in stages, manual controlled means mechanically operating said valve and automatically controlled means operating 55 said valve, each to a plurality of stages of braking, said means operatively connected with each other and said manual means being arranged to independently operate said valve to a stage of braking beyond the automatic operation.

2. A brake controlling mechanism for an air brake system comprising a brake valve for producing a brake application, manual controlled means and automatically controlled means mechanically connected for operating said valve and 65 arranged to independently operate said valve to apply the brakes, said manual controlled means having means associated therewith operating pneumatically for suspending the operation by said automatically controlled means.

3. A brake controlling mechanism for an air 70 brake system comprising a brake valve for producing a brake application, manual controlled means and automatically controlled means connected for operating said valve said manual con- 75

5 trol means having means associated therewith which, when operated to apply the brakes pneumatically suspends the operation of said automatically controlled means and when operated to release the brakes restores the automatic control.

10 4. A brake controlling mechanism for an air brake system comprising a brake valve for producing brake applications in stages, manual controlled means and automatically controlled means mechanically connected for operating said valve for different stages of braking, the automatically controlled means being dependent pneumatically upon the manual control means for braking to 15 the same extent as that produced by the manual control means and being independent of the manual control for increased braking effects.

20 5. A brake controlling mechanism for an air brake system comprising a brake valve for producing brake applications in stages, manual controlled means and automatically controlled means each operating said valve to a plurality of stages of braking, the manual controlled means, when in the application position, suspending the operation 25 of said automatically controlled means for the same degree of braking only and restoring the automatic control when operated to release the brakes.

30 6. A brake controlling mechanism for an air brake system comprising a brake valve for producing brake applications in stages, manual controlled means for operating said valve, automatically controlled means comprising a cylinder with a piston for independently operating said valve 35 and means whereby said manual controlled means controls the air supply to said cylinder.

40 7. A brake controlling mechanism for an air brake system comprising a brake valve for producing brake applications in stages, manual controlled means for operating said valve, automatically controlled means comprising a plurality of cylinders for operating said valve and means whereby said manually controlled means controls the air supply to said cylinders in different positions.

45 8. A brake controlling mechanism for an air brake system comprising a brake valve for producing a brake application, automatically controlled means comprising a cylinder for operating said valve, a speed control device and a stepping valve; said stepping valve alternately connecting said cylinder to exhaust and to said speed control device.

50 9. A brake controlling mechanism for an air brake system comprising a brake valve for producing a brake application, automatically controlled means comprising a cylinder for operating said valve, a forestalling device and a speed control valve, said forestalling device alternately connecting said cylinder to exhaust and to said speed control valve.

55 10. A brake controlling mechanism for an air brake system comprising a brake valve for producing a brake application, a spring normally acting to move said valve to the application position, a motion plate having a plurality of steps and a plunger controlled by each step of said motion plate and operating said valve.

60 11. A brake controlling mechanism for an air brake system comprising a brake valve for producing a brake application, a spring normally acting to move said valve to the application position, a manually positioned motion plate, a plunger controlled by said motion plate, and a dash

pot restricting the action of said plunger, said plunger operating said valve.

65 12. In a brake controlling mechanism for an air brake system for a vehicle, the combination, a brake valve for producing a brake application, a stepping valve controlling the operation of said brake valve, a magnet controlling the operation of said stepping valve and means, manually controlled, for preventing said magnet from making a succession of steps of said stepping valve.

70 13. An article of manufacture comprising a brake valve housing having a central cylinder with a manually operated valve therein and a second cylinder axially aligned with the first cylinder and having a piston therein controlling a valve by the difference in pressure on each side of said piston and an expansion reservoir surrounding said first cylinder and having a controlled connection with said second cylinder.

75 14. An article of manufacture comprising a brake valve housing having a central cylinder with a manually operated valve therein and a second cylinder axially aligned with the first cylinder and having a piston therein controlling a valve by the difference in pressure on each side of said piston, an expansion reservoir connected with said second cylinder, said connection being controlled by said manually operated valve.

80 15. A braking system for a railway vehicle comprising an air brake mechanism, a valve controlling said mechanism, means normally holding said valve in the non-controlling position means for rendering said holding means inactive and a Venturi tube mounted on said vehicle controlling said valve when said holding means is inactive.

85 16. A brake controlling system for a railway vehicle which operates in both directions, comprising an air brake mechanism, a valve controlling said mechanism, a double ended Venturi tube mounted on said vehicle having a longitudinal restricted air passage with end openings at right angles to said passage, means for deflecting air through said passage and means controlling the operation of said valve by said Venturi tube.

90 17. A brake controlling system for a railway vehicle which operates in both directions, comprising an air brake mechanism, a valve controlling said mechanism, a double ended Venturi tube mounted on said vehicle having a longitudinal restricted air passage with end openings at right angles to said passage, means for deflecting air currents through said passage, a tube in said restricted passage controlling said valve and means controlling the orifice of said tube by the direction of the air currents through said passage.

95 18. A brake controlling system comprising a brake valve having a cylinder with an equalizing piston, an exhaust valve controlled by said piston, an expansion reservoir connected by a port with said cylinder and a valve operated by said piston for opening and closing said port.

100 19. A brake controlling system comprising a mechanism having a cylinder with an equalizing piston, an exhaust port, and an expansion reservoir connected with said cylinder by a port, said piston in one position closing said exhaust port and opening the port to said reservoir and in another position opening said exhaust port and closing the port to said reservoir.

105 20. In an air brake system, the combination, a brake pipe, a vent port, an equalizing valve connecting said brake pipe with the vent port,

- 5 a piston controlling said valve, means for equalizing the pressure on said piston to close said vent port, means for releasing the pressure on said piston to open said vent port and means operated by said piston controlling the release of pressure on said piston.
- 10 21. In an air brake system, the combination, a brake pipe, a vent port, an equalizing valve connecting said brake pipe with said vent port, a piston controlling said valve, means for equalizing the pressure on said piston to close said vent port, and means for releasing the pressure on said piston intermittently to open said vent port, said releasing means being controlled by 15 said piston.
- 20 22. In an air brake system, the combination, a cylinder with an equalizing piston therein, a port in each end of said cylinder, means associated with said piston for closing the port at one end and opening the port at the opposite end of said cylinder and when the piston is reversed for reversing this condition, an air brake pipe connected with one of said ports and an equalizing pressure connected with the other port.
- 25 23. In a brake controlling system for a vehicle, the combination, a brake valve for producing a brake application, a stepping valve controlling the operation of said brake valve, a magnet controlling the operation of said stepping valve and means preventing a succession of steps of said stepping valve when said valve is in the application position.
- 30 24. A brake controlling mechanism for an air brake system comprising a brake valve for producing a brake application, manual controlled means for operating said brake valve, automatic controlled means for operating said brake valve and a walking beam connecting said means with said brake valve.
- 35 40 25. A brake controlling mechanism for an air brake system comprising a brake valve for producing a brake application, a plurality of automatically controlled means for operating said brake valve and a walking beam connecting said means with said valve.
- 45 50 26. A brake controlling mechanism for an air brake system comprising a brake valve for producing a brake application, a plurality of means for operating said brake valve and a compound walking beam connecting said means with said valve.
- 55 27. A brake controlling mechanism for an air brake system comprising a brake valve for producing a brake application, a plurality of means including a motion plate for operating said valve and a walking beam connecting said means with said valve.
- 60 65 28. A braking system for a railway vehicle comprising an air brake mechanism, a valve controlling said mechanism, means normally holding said valve in the non-controlling position, and a Venturi tube on said vehicle having a longitudinal restricted air passage with an end opening at right angles to said passage, means for deflecting air through said passage, said Venturi tube controlling said valve when said controlling means releases control of said valve.
- 70 29. In a controlling system, the combination,
- 5 a control valve having an active and an inactive position, a magnet when energized, maintaining said valve in the inactive position, a Venturi tube and a valve controlled thereby for controlling said first named valve when said magnet is deenergized.
- 10 30. A brake valve comprising a cylindrical housing with a valve therein having a projecting stem and a motion plate passing around said cylinder and operatively connected with said stem for operating said valve.
- 15 31. A brake valve comprising a cylindrical housing with a valve therein said housing having a central projecting stem and a rotary valve centered about said stem to be operated without interfering with the free movement of said stem.
- 20 32. A brake valve comprising a cylindrical housing with a valve therein having a central sliding stem and an independent rotary valve centered about said stem.
- 25 33. A brake valve for an air brake system comprising a central valve chamber with a valve therein and a plurality of expansion reservoirs circumferentially arranged about said chamber, said valve controlling the connections to said reservoirs.
- 30 34. A brake valve for an air brake system comprising a control valve biased by a spring to the application position and a dash pot for retarding the action of said valve towards the control position.
- 35 40 35. A mechanism for controlling a braking system in stages comprising a first device automatically operated for operating said mechanism to the first stage of braking, a second device also operating the mechanism to the first stage of braking, each device operating independently of the other, and said devices when operated at the same time co-operatively operating said mechanism to the second stage of braking.
- 45 55 36. A mechanism for controlling a braking system in stages comprising a plurality of means, automatically operated, each for independently operating said mechanism to the same stage of braking and for cooperatively operating said mechanism to two stages of braking and manually operated means for operating said mechanism to three stages of braking.
- 50 55 37. A mechanism for controlling a braking system in stages comprising a plurality of means, automatically operated from the track, each, for independently operating said mechanism to the same stage of braking and for cooperatively operating said mechanism to two stages of braking and manually operated means cooperating with said automatic means to increase the stages of brake application, but not to release the stages of braking automatically applied.
- 60 65 38. A mechanism for controlling a braking system in stages comprising a valve having three brake applying positions, a plurality of means, automatically operated, each for independently operating said valve to one stage of braking and for cooperatively operating said valve to two stages of braking and manual means for operating said valve to the third stage of braking.

MATTHEW H. LOUGHRISE.
